MULTI-COMPARTMENT CABINET

Philip H. Band, New York, N. Y.

Application April 21, 1955, Serial No. 35,624

Term of patent 14 years

(Cl. D33—19)

Figure 1 is a perspective view of a multi-compartment cabinet, showing my new design, the master door being shown closed, and one of the individual locker doors being shown open for illustrative purposes;

Figure 2 is a similar view, with the master door opened;

Figure 3 is a top plan view;

Figure 4 is an enlarged fragmentary perspective view showing one of the individual locker doors partly open;

Figure 5 is a similar view with the door open; and

Figure 6 is a cross-sectional view substantially along the line 6-6 of Figure 5.

The design is characterized by the relatively tall and narrow dimensions of the cabinet in proportion to the relatively low heights of the superposed lockers each of which has a horizontally elongated door hinged at one of its narrow ends; also by the offset margin of the opposite narrow end of each locker door in association with the specific handle and data bearing elements arranged as shown.

I claim:

The ornamental design for a multi-compartment cabinet, substantially as shown and described.
